UNITED STATES PATENT OFFICE.

FREDERICK H. RAGAN, OF DETROIT, MICHIGAN.

POWER PRESS.

Application filed August 12, 1921. Serial No. 491,703.

To all whom it may concern:

Be it known that I, FREDERICK H. RAGAN, a citizen of the United States, residing at Detroit, in the county of Wayne and State 5 of Michigan, have invented certain new and useful Improvements in Power Presses, of which the following is a specification.

My invention relates to a power press suitable for light or heavy press work, the pressure applied being controlled entirely by the operator through simple, efficient mechanism. The construction and arrangement are such that the press is flexible as to power, from a few pounds to many tons, the 10 pressure exerted depending upon and being in direct relation to the pressure applied by the operator on an actuating lever such as a foot pedal. Moreover the ram is provided with a considerable stroke whereby a wide 15 range of movement is provided for push broaching, pressing in bushings, assembling gears to shafts and so forth. Moreover the ram is operated by direct worm drive from the pulley and the usual operating connections such as rack and pinion or spur or 20 beveled gears are dispensed with. Other novel and advantageous features of construction and operation will be apparent from the description hereinafter given.

30 In the drawing Fig. 1 is an elevation of a press embodying my invention; Fig. 2 a vertical section on the line 2—2 of Fig. 3; Fig. 3 a sectional plan view on the line 3—3 of Fig. 2; Fig. 4 a cross section on the line 35 4—4 of Fig. 2, and Fig. 5 a detail section of the upper end of the ram and column.

Referring to the particular embodiment of my invention as herein shown, the press frame comprises the usual base 1, a vertical 40 column 2, supporting bracket 3 for the usual fast and loose pulleys 4, a vertically adjustable table 5, a horizontal drive shaft 6 and operating connections between this shaft and the ram 7. These operating connections together with the particular construction of ram constitutes the subject matter of 45 this invention.

The drive shaft extends into and is journaled in a casing 8 which extends from one 50 side of the axis of the ram. This shaft is provided at a point within this casing with a worm 9 meshing with a worm gear 10 whose extended hub 11 is mounted concentric of the ram 7. This hub is secured to diametrically opposite vertical spline keys 12 which 55 are received in the vertical or longitudinal

key-ways 13 in the ram which key-ways extend not only through the lower smooth portion of the ram but also through the screw threaded portion thereof. The hub 11 has 60 its bearing within the bushing 15 which is located in the vertical bearing 16 of the casing structure 17 of which the casing 8 is a part. This casing structure is preferably made in two parts which are held together 65 by the bolts 18.

The ram extends upwardly through the vertical cylinder 19 and is connected at its upper end to a cable 20 which runs over a pulley 21 and is provided at its lower end 70 with a counterweight 22 whereby the ram may be returned automatically and rapidly to normal position when permitted to do so by the position of the operating connections and at the will of the operator.

At the lower end of the cylinder 19 which is here a part of the column 2 there is arranged a nut 23 which is here in the form of a pulley provided with a rim 24. This nut has a central threaded bore which screws 75 upon the screw portion 14 of the ram. This nut is interposed between the lower end of the cylinder 19 and the upper end of the bearing 16 of the casing structure 17 and because of the vertical thrust and anti-friction bearing 25 is provided between this nut and the lower end of the cylinder 19 as shown in Fig. 2.

The nut 23 and its rim 24 constitute the control member of the press and cause the 90 longitudinal movement of the ram, when such member is held stationarily by suitable means under the control of the operator. These means in the present instance consist of a band brake 26 cooperating with 95 the periphery of the rim and adapted to be actuated by the operator's foot through a pedal 27 and connections between it and the band. This band is preferably asbestos lined and is of the anchored pull-end type 100 whereby when the pedal is operated the band is tightened frictionally on the rim. As shown in Fig. 3, one end of the band 26 is anchored to the pin 28 in the main frame and the other end is connected to a head 29 105 adjustably secured as by screw threading to a rod 30. This rod works through and is guided by an opening 31 in the frame and is connected to the vertical arm of a bell crank 32 whose horizontal arm is connected by a 110 vertical rod 33 with the pedal 27 intermediate the length thereof, as shown in Fig. 1.

As shown in Fig. 5 the cable 20, is connected with the ram through a swivel connection, including a yoke 34, cross pin 35 to which the cable is attached, ball bearings 36 surrounding the projecting stem 37 of the ram and interposed between the bottom of the yoke and a nut 38 screwing on the outer end of said stem. This yoke is held stationarily but permitted of a longitudinal movement by means of the projection in the form of a screw 39 secured to one side of the yoke and adapted to travel in an interior slot 40 in the column 19. This column is closed by a top cap 41 which constitutes a safety stop to prevent over-travel of the ram. The cable 20 passes through an opening 42 in this cap which is removably secured to the top of the column in a suitable manner as by the set screws 43.

20 Describing the operation the ram is rotated at a constant speed in one direction by the worm drive and splines above described. The control member which includes the nut 23 and rim 24 revolves with the ram until 25 pressure is applied by the operator to the foot pedal whereupon the brake band 26 is tightened on to the rim of the control member and the latter is thereby held stationary. As a result the ram will be advanced or 30 moved longitudinally, that is, fed downwardly toward the table 5 in the present instance. This longitudinal movement continues until the pressure on the foot pedal is released at which time the counterweight 22 35 returns the ram quickly to its up or normal position, the nut or control member rotating so as to permit the ram to move longitudinally upwardly, that is, to feed through the nut.

40 The above described press is extremely flexible as to the power applied at the will of the operator, such power or pressure varying from a few pounds to many tons, depending entirely upon and being in direct 45 relation to the pressure applied by the operator on the foot pedal. Moreover the ram stops whenever the pressure on the pedal is released or whenever the pressure on the work balances in direct relation to the pressure applied on the pedal by the brake band 50 which is capable of slipping to take care of abnormal load, thus preventing any chance of breakage. Owing to the fact that the length of stroke and pressure applied is at 55 all times controlled by the operator, this press is particularly adapted for all kinds of straightening work. Furthermore, the construction is such that the ram is given a long and steady stroke and chatter is 60 avoided.

I claim:

1. A power press including a longitudinally movable ram, means for rotating the ram, and a control member mounted directly 65 on the ram for rotary movement thereon and

thereof, said ram and control member having cooperating parts whereby the ram is moved longitudinally slowly in one direction for feeding purposes and is permitted to move rapidly in the opposite direction. 70

2. A power press including a longitudinally movable ram, means for rotating the ram, and a control member, said member being mounted upon the ram and capable of rotary movement therewith and having means whereby it may be held stationary at the will of the operator, said ram and control member having cooperating parts whereby the ram is moved longitudinally slowly in one direction for feeding purposes when such member is held stationary and is permitted to move rapidly in the opposite direction. 75

3. A power press including a longitudinally movable ram having a screw threaded portion and an extended longitudinal key-way, a drive wheel having a key cooperating with said key-way, a control member threaded upon said screw portion of the ram, and means under the control of the operator for holding said member stationary. 80

4. A power press including a longitudinally movable ram having a screw threaded portion and an extended longitudinal key-way, a drive wheel having a key cooperating with said key-way, a control member threaded upon said screw portion of the ram, and means under the control of the operator for holding said member stationary, comprising a friction band cooperating with 85 said member.

5. A power press including a longitudinally movable ram having a screw threaded portion and an extended longitudinal key-way, a drive wheel having a key cooperating with said key-way, a control member consisting of a rim and a nut threaded upon said screw portion of the ram and a friction band cooperating with the rim to hold control member stationary at the will of the operator. 105

6. A power press including a longitudinally movable ram, means for rotating the ram, and a control member, said ram and control member having cooperating parts whereby the ram is moved longitudinally slowly in one direction for feeding purposes and is permitted to move rapidly in the opposite direction, and yielding means tending to hold the ram in normal position and resisting the feeding movement of the ram but yielding for feeding purposes. 110

7. A power press including a longitudinally movable ram having a screw threaded portion and an extended longitudinal key-way, a drive wheel having a key cooperating with said key-way, a control member consisting of a rim and a nut threaded upon said screw portion of the ram and a friction band cooperating with the rim to hold 115 120 125 130

control member stationary at the will of the operator, and yielding means tending to hold the ram in normal position and capable of restoring it to such position when said band is released from the rim.

8. A power press including a frame having a column, a ram contained within the column and extending therebelow, said ram having a screw threaded portion, a control member including a nut threaded onto such screw threaded portion and located at the lower end of the column and adapted to bear theragainst, a casing on the frame, and a drive wheel therein having spline connection with the ram.

9. A power press including a frame having a column, a ram contained within the column and extending therebelow, said ram having a screw threaded portion, a control member including a nut threaded onto such screw threaded portion and located at the lower end of the column and adapted to bear theragainst, a casing on the frame, a drive wheel therein having a central bore, and a bushing secured in said bore and having an internal spline, said ram having a smooth portion at its outer end and a key-way extending longitudinally through such smooth portion and such screw threaded portion and engaged by such spline.

10. A power press including a longitudinally movable ram having a screw threaded portion and an extended longitudinal key-way, a drive wheel having a key cooperating with said key-way, a control member consisting of a nut having a rim and threaded upon said screw portion of the ram, a friction brake band cooperating with the rim to hold the control member stationary, and a foot treadle and connections under the control of the operator for operating the band.

11. A power press including a longitudinally movable ram, means for rotating the ram, and a control member mounted directly on the ram for rotary movement thereon and thereof, said ram and control member having cooperating parts whereby the ram is moved longitudinally slowly in one direction for feeding purposes and is permitted to move rapidly in the opposite direction, and means for limiting the movement of the ram in such latter direction.

12. A power press including a frame having a column, a ram contained within the column and extending therebelow, said ram having a screw threaded portion, a control member including a nut threaded onto such screw threaded portion and located at the lower end of the column, means for rotating the ram, and means for limiting the return movement of the ram.

13. A power press including a frame hav-

ing a column, a ram contained within the column and extending therebelow, said ram having a screw threaded portion, a control member including a nut threaded onto such screw threaded portion and located at the lower end of the column, means for rotating the ram, and a cap on the top of the column to limit the return movement of the ram.

14. A power press including a frame having a column, a ram contained within the column and extending therebelow, said ram having a screw threaded portion, a control member including a nut threaded onto such screw threaded portion and located at the lower end of the column, means for rotating the ram, a counterweight, a cable thereon, and a swivel connection between the cable and the ram.

15. A power press including a frame having a column, a ram contained within the column and extending therebelow, said ram having a screw threaded portion, a control member including a nut threaded onto such screw threaded portion and located at the lower end of the column, means for rotating the ram, a counterweight, a cable thereon, and a swivel connection between the cable and the ram, comprising a yoke to which the cable is attached and which is mounted on one end of the ram, a nut on such end of the ram and an anti-friction bearing between the nut and the yoke.

16. A power press including a frame having a column, a ram contained within the column and extending therebelow, said ram having a screw threaded portion, a control member including a nut threaded onto such screw threaded portion and located at the lower end of the column, means for rotating the ram, a counterweight, a cable thereon, and a swivel connection between the cable and the ram, comprising a yoke to which the cable is attached and which is mounted freely on the one end of the ram, and means for preventing rotation of the yoke.

17. A power press including a frame having a column, a ram contained within the column and extending therebelow, said ram having a screw threaded portion, a control member including a nut threaded onto such screw threaded portion and located at the lower end of the column, means for rotating the ram, a counter-weight, a cable thereon, and a swivel connection between the cable and the ram, comprising a yoke to which the cable is attached and which is mounted freely on the one end of the ram, and means for preventing rotation of the yoke, comprising a projection on one side of the yoke, the interior of the column having a longitudinal groove in which such projection travels.

FREDERICK H. RAGAN.
